BEVERAGE CARTON CARRIER

Frederick C. Hendy, Aspen, Colo.

Application December 26, 1956, Serial No. 44,329

Term of patent 14 years

(Cl. D58—26)

Fig. 3

I claim:

The ornamental design for a beverage carton carrier, as shown.
